UNITED STATES PATENT OFFICE.

CYRUS B. WHITE, OF ORANGEVILLE, PENNSYLVANIA.

FEED-CUTTER.

SPECIFICATION forming part of Letters Patent No. 592,855, dated November 2, 1897.

Application filed December 31, 1895. Serial No. 573,919. (No model.)

To all whom it may concern:

Be it known that I, CYRUS B. WHITE, a citizen of the United States, residing at Orangeville, in the county of Columbia and State of Pennsylvania, have invented a new and useful Feed-Cutter, of which the following is a specification.

This invention relates to an improvement in feed-cutters, and has for its object to simplify and improve the general construction of machines of the class referred to with a view to adapting the same to cut the fodder, hay, or straw, as the case may be, and in the case of fodder to tear and crush the same after it has been cut up by the knives and before it is discharged from the machine, thus producing a superior grade of ensilage or resultant material which will be softer and more easily eaten by cattle.

Other detailed objects and advantages of the invention will be developed in the course of the subjoined description.

The invention consists in certain novel features and details of construction and arrangement of parts, whereby advantages in point of simplicity, ease of operation, and efficiency are attained, as hereinafter fully described, illustrated in the drawings, and finally embodied in the claim hereto appended.

In the accompanying drawings, Figure 1 is a perspective view of a feed - cutter constructed in accordance with the present invention. Fig. 2 is a plan view of the same. Fig. 3 is a side elevation taken from the left-hand side of the machine. Fig. 4 is a vertical longitudinal section through the machine. Fig. 5 is a vertical transverse section through the machine, taken in line with the feed-rolls. Fig. 6 is a detail side elevation taken from the right-hand side of the machine with the gear-wheels removed and the cutter-shaft and the lower feed-roll shaft in section. Fig. 7 is a detail perspective view of the vertically-adjustable double concave. Fig. 8 is a similar view of the longitudinally - adjustable ledger-blade. Fig. 9 is a similar view of one of the guide-sockets for the removable front board of the machine, the front board being shown in dotted lines. Fig. 10 is a detail plan view showing the manner of throwing the feed-rolls out of action, also showing the

application of a sprocket-wheel of different size to the upper feed-roll shaft.

Similar numerals of reference designate corresponding parts in the several figures of 55 the drawings.

Referring to the accompanying drawings, 1 designates a suitable frame upon which the feed-trough and various parts of the machine are mounted. This frame comprises in its 60 construction a pair of elevated longitudinal timbers 2, arranged in parallel relation to each other and spaced apart a distance regulated by the width of cut which it is desired to give to the machine. The feed-trough 3 65 is supported upon the timbers 2 and is of any usual or preferred construction, being shown as having the usual converging sides for compacting the material as it progresses toward the cutting-cylinders. At its inner end the 70 trough 3 is provided with a deflector 4, superposed above such inner end and adapted to direct the material as it is fed to the cutting mechanism. At the inner end of the feed-trough is located a pair of feed-rolls, 5 75 indicating the lower feed-roll, which has a smooth peripheral surface and works through an opening in the bottom of the trough, and 6 a toothed or spiked roll arranged above the smooth roll and having its peripheral surface 80 covered with numerous teeth or spikes, preferably of pyramidal form, the points of said teeth being adapted to operate normally in proximal relation to the periphery of the smooth roll. The smooth roll is journaled in 85 stationary bearings on the machine-frame, while the spiked roll is journaled in eye-bearings 7, each of which is provided with a downwardly-extending curved stem or shank 8, which passes through one of the frame- 90 bars 2, and is provided beneath the same with a surrounding tension-spring 9, and also at its extremity with a winged nut 10, by means of which the tension of said spring 95 may be adjusted. The shaft of the spiked 95 or toothed feed-roll is itself mounted in and adapted to slide longitudinally of an oppositely-disposed pair of upwardly and rearwardly extending segmental guides 11, the curves of said guides 11 and the stems or 100 shanks 8 being struck upon a common circle. By means of this construction the upper feed-

roll is capable of yielding automatically to accommodate the thickness of the material passing between the rolls and is moved across the discharge-mouth of the cutter-box. The 5 arc of the circle upon which the guides 11 are struck is primarily derived from the rear-most shaft of the machine or the shaft from which the upper feed-roll directly receives its motion, as will hereinafter appear, so that 10 the said feed-roll will not be thrown out of gear when it yields to accommodate the feed.

Arranged just in front of the smooth feed-roll 5 and depending from the floor of the feed-trough is a stationary transversely-disposed board 12, constituting the rear wall of 15 an intermediate hopper 13, into which the cut material is discharged. This hopper is also defined by stationary side walls, as shown, and by a removable front wall 14, 20 slidably seated in socket-pieces 15, secured in vertical disposition to the inner surfaces of the side walls of the hopper 13, as shown in Fig. 4. This removable front board is provided with shoulders 16 for limiting the downward movement thereof, and its upper end lies within an arched hood 16^a, pivoted, as at 25 17, to the machine-frame and extending over and covering the cutting-cylinder 18. By 30 rocking the hood 16 upon its hinge the front board 14 may be removed and replaced, as desired.

The cutting-cylinder 18 is mounted in bearings on the machine-frame and is located at the upper end of the intermediate hopper 13, 35 its shaft 19 lying approximately in the horizontal plane of the meeting-points of the feed-rolls 5 and 6, above described. The cylinder 18 preferably has two spirally-disposed knives 20, arranged diametrically opposite and operating against a stationary ledger-blade 21. The active face of the ledger-blade is located 40 normally in the circumferential plane of the cutting-cylinder knives, while its upper surface is arranged flush with the floor of the 45 feed-trough, as shown in Fig. 4. The ledger-blade is also provided at each end with slotted rearward extensions 22, which rest upon the frame-timbers 2, clamping-bolts 23 being passed through such slotted extensions and 50 frame-timbers, whereby the ledger-blade may be advanced toward the knives 20 for the purpose of taking up wear and bringing the rotary knives and stationary blade into proper working relation.

55 In the bottom of the intermediate hopper 13 is arranged a pair of crushing-rolls 24, mounted upon transverse shafts suitably journaled in the machine-frame by means of angle-brackets 25. The shafts of the crushing-rolls 60 are geared together by means of spur-gears 26 upon their adjacent ends, so as to rotate simultaneously in opposite directions. The crushing-rolls 24 are provided with similar pyramidal teeth upon their peripheral surfaces 65 which co-operate with similar teeth on a double concave 27 to tear and crush the fodder, so as to make it soft and easily eaten by

cattle. The concave 27 has its upper toothed surface reversely inclined or curved to correspond approximately to the shape of the 70 crushing-rolls, the central ridge or vertex of said concave, which is of inverted-V shape, being located in a vertical plane passing midway between the said crushing-rolls. At each end the concave is provided with depending 75 slotted extensions 28, through which clamping-bolts 29 pass into downward extensions 30 of the machine-frame. By means of this construction it is possible to adjust the double concave vertically and bring the working 80 surfaces thereof into the desired relation to the crushing-rolls for adapting them to tear and mash the fodder, either slightly or considerably.

It will be understood that the crushing-rolls 85 turn toward each other from the top and carry all the fodder across the concave, finally discharging the same from the machine.

An important feature of the present invention is the provision or means just described 90 for tearing and crushing the fodder after it has been cut, so as to produce a superior grade of ensilage sufficiently fine and soft so as to be easily eaten or chewed by cattle, and in the accomplishment of this result the 95 particular formation of the concave 27 is of special importance. The two crushing-rolls 24, as well as the concave 27, are provided with teeth of a pyramidal form, which form of teeth insures a tearing and crushing of the 100 fodder without a further cutting thereof, and by reference to Fig. 7 of the drawings it is to be observed that the concave is provided at its crest or vertex with relatively large 105 teeth, while the teeth at each side of the crest or vertex gradually and progressively diminish in size toward the opposite side edges of the concave. The larger teeth of the concave at the crest or vertex thereof lie in the space 110 between the two crushing-rolls and project in sufficiently close proximity to the rolls to insure a tearing and crushing of the fodder at the initial point of its movement between the concave and the rolls.

Motion is primarily imparted to the machine 115 by means of a belt from any suitable power running over either member or rim of a double pulley and combined fly-wheel 31, which is fast upon one end of the shaft 19 of the cutting-cylinder, the said rims 31 being of different diameters, so as to provide for varying the speed of the machine. Upon the opposite end of the cutting-cylinder shaft is fixedly mounted a sprocket-wheel 32, from which a sprocket-chain 33 extends around a sprocket- 120 pinion 34, fast on the end of one of the shafts of the crushing-rolls 24, whereby the latter are driven. Upon the same shaft 19 outside of the sprocket-wheel 32 are fixedly mounted two spur-gears 35 and 36, the outside and 125 larger one of which meshes with a spur-gear 37, loosely mounted upon the extremity of the shaft 38 of the smooth feed-roll 5. The spur-gear 37 has a crank-handle 39 rigidly

attached thereto, by means of which the machine may be driven by hand-power, when desired. Inside of the gear 37 and fast on the shaft 38 of the smooth feed-roll is a spur gear-wheel 40, which meshes with and is driven by the small pinion 36 on the shaft of the cutting-cylinder, motion being thus imparted to the smooth feed-roll 5. The gear 40 meshes with and drives a similar gear 41, fast on a transverse shaft 42, arranged beneath the feed-trough, the latter shaft having feathered upon its opposite end a sliding sprocket-wheel 43, from which a chain 44 extends to and around a sprocket-wheel 45, fast upon the adjacent end of the upper spiked feed-roll shaft 46. The segmental guides 11 being described on the arc of a circle of which the shaft 42 is the center it will be seen that the upper feed-roll is capable of yielding or being adjusted without interfering with its operation.

47 designates a guide-pulley for directing the drive-chain 44.

The sprocket-wheel 43, as above stated, is feathered upon the shaft 42 and capable of sliding longitudinally thereof. The said sprocket-wheel has a grooved lateral extension or hub 48, adapted to be engaged by one end of an intermediately-pivoted shipping fork or lever 49, mounted on a fulcrum-bracket 50, secured to one side of the feed-trough. The grooved hub 48 of the sprocket-wheel 43 is also formed with a clutch-face 51, adapted to engage a transverse pin 52, passing through the extremity of the shaft 42. The sprocket-wheel 43 may thus be thrown into and out of engagement with the pin 52, and consequently the shaft 42, by vibrating the shipping-lever 49, and the engagement between said sprocket-wheel and the pin 52 is normally preserved by means of an expansive spring 53, interposed between the shipping-lever and the frame of the machine or feed-trough.

45 The construction last described enables the force-feed rolls to be immediately thrown out of operation when required, which serves to relieve the necessity of choking down the feed and also enables the operator to avert serious accidents.

It will be noted that in Fig. 10 the sprocket-wheel 45 on the end of the shaft 46 is of smaller diameter than the corresponding

sprocket shown in Fig. 2. Interchangeable sprockets of varying diameters may be used 55 to advantage at this point for varying the rapidity of feed of the rolls 5 and 6.

By means of the construction above described a combined fodder cutter and crusher is obtained which will cut hay and straw 60 equally as well. The machine may be used also as a simple cutter by detaching the drive-chain 33, so as to throw the crushing-rolls 24 out of operation and by removing the front slide-board 14, thus allowing the cut material 65 to be discharged above said crushing-rolls. By reason of the particular form of gearing shown and described the crushing-rolls are driven at relatively high speed, and the machine may be operated either by hand or 70 power. The toothed or spiked and positively-driven yielding feed-roll 6 is also found decidedly advantageous over the ordinary longitudinally fluted or corrugated roll. Considered as a whole the feed-cutter is exceedingly light-running, is capable of being adjusted to the particular kind of material operated upon, or so as to cut the same with any required degree of fineness.

Changes in the form, proportion, and minor 80 details of construction may be resorted to without departing from the spirit or sacrificing any of the advantages of this invention.

Having thus described the invention, what is claimed as new is—

In a feed-cutter, the combination with the cutting-cylinder, its actuating mechanism, and the pivoted hood covering said cylinder, of a trough or hopper underlying said cylinder, a pair of positively-driven toothed crushing-rolls journaled in the bottom of said trough or hopper, an adjustable concave located beneath said rolls, provision for throwing said rolls out of operation and a removable front wall to said hopper the same consisting of a board sliding vertically in grooves in the opposite sides of the machine-frame, substantially as described.

In testimony that I claim the foregoing as my own I have hereto affixed my signature in 100 the presence of two witnesses.

CYRUS B. WHITE.
